Primary Examiner — Kevin Rudzinski*Assistant Examiner* — Sean D Lough(74) *Attorney, Agent, or Firm* — Scheinberg & Associates, PC; Michael O. Scheinberg**CLAIM**

I claim the ornamental design for the thigh drum, as shown and described.

DESCRIPTION

FIG. 1 is a front perspective view of a thigh drum according to the present design.

FIG. 2 is a back perspective view thereof.

FIG. 3 is a top plan view thereof.

FIG. 4 is a bottom plan view thereof.

FIG. 5 is an elevation view from the left side thereof.

FIG. 6 is an elevation view from the right side thereof.

FIG. 7 is a front elevation view thereof; and,

FIG. 8 is a back elevation view thereof.

The broken line showing of the thumb hole and decoration illustrate portions of the thigh drum that form no part of the claimed design.
